UNITED STATES PATENT OFFICE.

MYRON W. PARRISH, OF DETROIT, MICHIGAN, ASSIGNOR OF THREE-TENTHS
TO STEPHEN K. STANTON, J. H. CARSTENS, AND FREDERICK T. SIBLEY,
OF SAME PLACE.

ELECTRIC TRAIN-SIGNAL.

SPECIFICATION forming part of Letters Patent No. 548,924, dated October 29, 1895.

Application filed December 24, 1894. Serial No. 532,830. (No model.)

To all whom it may concern:

Be it known that I, MYRON W. PARRISH, a citizen of the United States, residing at Detroit, in the county of Wayne, State of Michigan, have invented a new and useful Electric Train-Signal, of which the following is a specification.

This invention especially relates to that class of electric train-signaling apparatuses for conductors' use in signaling the engineer in which two circuits are employed, one of them being styled the "bell-circuit" and the other the "train-circuit."

The object of my invention is to insure greater certainty in the action of the signal and to enable the engineer to know when the bell rings by express design of the conductor or by accident or by lack of sufficient electric energy to prevent the bell from ringing when it otherwise should ring.

To this end I employ, in general terms, a bell-circuit, a train-circuit, a battery or other source of electric energy common to both of said circuits, the bell-circuit being normally open and the train-circuit being normally closed, and both of said circuits never being nor remaining closed at one and the same time, and a magnetically-controlled circuit maker and breaker which is operated by the train-circuit and by virtue of its own peculiar construction and operates upon the bell-circuit to make and break the same, all as more particularly described and claimed below.

In the drawing forming a part of this specification is shown a diagrammatical view of my apparatus, the bell and the circuit maker and breaker being in perspective.

Referring to the lettered parts of the drawing, A is the bell or signal, which for clearness of description we will suppose to be in the cab of an engine, (not here shown;) B, the battery or other source of electric energy, and C the bell-circuit. This bell-circuit is normally open, the severed or disconnected ends of the circuit-wires being attached, respectively, to metallic terminal plates D, which plates are separated, but contiguous to each other and preferably elastic, said bell-circuit, of course, being connected with the battery B. The train-circuit E E also connects with the battery B, and we will suppose it to be extended

throughout the train of cars. (Not here shown.)

As many circuit makers and breakers F are employed as necessary; but one will serve to illustrate the idea, this one F being for the conductor's use in the train to break the train-circuit with. This train-circuit is normally closed, as stated, and shown in the drawing. In this train-circuit E E are magnets H.

At I is an armature-lever between the metallic terminals D of the bell-circuit C C and the magnets H of the train-circuit E E. This armature-lever I is fulcrumed at J between its two ends and at a point sufficiently near the end next to the magnets to permit or cause the other end to overbalance it when the train-circuit is broken, and thus lower by gravity to contact with the circuit-terminals D to make the bell-circuit C C. Said heavier end of the armature-lever I is provided with a contact-point L, adapted to enter between the circuit-terminals D and contact with both to close the bell-circuit.

To always insure a certain and sufficiently close and steady contact of the contact-point L with the circuit-terminals D, which jar of the engine or other causes might interfere with, I provide a spring N, attached to the end of the armature-lever I in a manner that the action of said lever to disconnect the contact-point L from the circuit-terminals D will be against a slight spring resistance.

The fulcrumed armature-lever I, with its contact-point L, the magnets H, and circuit-terminals D constitute the circuit maker and breaker.

While I design and have described my invention as especially adapted for train service, it can of course be employed on boats and for any and all signaling and alarm purposes desired.

As illustrated, the bell-circuit C C is open and the train-circuit E E is closed, as stated. This is the normal condition, both circuits never being closed at the same time, and when in this condition the bell A remains silent, since the magnets H hold one end of the armature-lever I in contact therewith, and the other end of said lever is disconnected from the terminals D of the bell-circuit. Any breaking of the train-circuit E E releases the

armature-lever I from contact with the magnets H, at which time the heavier end of said lever falls by gravity, contacting with the circuit-terminals D, and the bell A rings until 5 the train-circuit is again closed. This breaking of the train-circuit E E might be caused either by express design of the conductor in operating the circuit maker and breaker F in one of the cars of the train, by act of 10 train-robbers in cutting the circuit-wires between the cars, or by accidental separation of the train. The engineer can tell by the peculiar nature of the signal when the break is made by the conductor.

15 The only instance in which the bell might sound when the train-circuit has not been broken is in case the electric energy became too weak to cause the magnets H to hold the end of the armature-lever I in contact there- 20 with, or at least continuously in contact, in which case (which by proper care and attention need never happen) the engineer would know the cause from the peculiar continuous and intermittent faint jingling of the bell, and 25 the electric energy could be at once renewed. This feature is very important, since it obvi- 30 ates any necessity for the engineer to test the battery to ascertain if the electric energy is becoming too weak and which he might for- 35 get to do if there was any provision for so doing—as, for instance, in prior systems em- 40 ploying a key to be removed to break the cir- 45 cuit or other mechanical contrivances which have to be manipulated by hand to test the 50 strength of the battery. It is further im- 55 portant, since the peculiar intermittent weak 60 jingling of the bell shows the engineer a lack of sufficient electric energy which could be 65 produced from no other cause, since it is the 70 condition of the electric energy itself which 75 operates to produce the signal, and this being 80 automatic, by virtue of the construction and 85 relation of parts, gives the warning without 90 any need of forethought or attention on the 95 part of the engineer. This results from the 100 fact, as stated, that the armature-lever I is 105 horizontally supported on a fixed fulcrum 110 between its two ends, so that the end which 115 is over the vertically-upright circuit-termi- 120 nals overbalances the other end by gravity 125 when the normally-closed circuit is broken, so that it nearly balances on said fulcrum and intermittently rocks thereon when the electric energy becomes too weak, because the then weak attraction of the magnets for the end of the armature-lever over them in- 130 termittently resists the attraction of gravity for the other end, and thus produces the con- 135 tinuous signaling of the nature described, and without any mechanical manipulation of 140 parts by an operator and without the mak- 145 ing or breaking of either circuit.

While I do not claim to be the first to em- 150 ploy a normally-open in connection with a 155 normally-closed circuit in a system in which a breaking of the latter circuit operates to 160 cause the former to sound a signal, yet so far

as I know such a system is new with me in which the armature-lever is so constructed and arranged in relation to the magnets and 70 circuit-terminals that a weakened condition of the electric energy itself operates to give a warning signal to the engineer of the na- 75 ture described.

Having thus described my invention, what 75 I claim as new, and desire to secure by Letters Patent of the United States, is—

1. An electric signaling apparatus, com- 80 prising a circuit having separated contiguous circuit terminals projecting vertically up- 85 ward from a horizontal base, a signal in said circuit, a closed circuit having signaling cir- 90 cuit-breakers therein at locations from which the signal is to be sent, a source of electric energy, and a fulcrumed overbalancing ar- 95 mature-lever adapted to operate to intermit- 100 tingly contact with said circuit-terminals by an undue diminution of the electric energy, and to make positive contact by operating a circuit-breaker to break the closed circuit, 105 substantially as set forth.

2. An electric signaling apparatus, com- 110 prising a normally closed circuit, magnets in 115 said circuit, a normally open circuit and a signal in said circuit, and having the metal- 120 lic separated circuit-terminals, a source of 125 electric energy common to both circuits, and 130 a lever between the magnets and circuit-termi- 135 nals, said lever being fulcrumed at such a 140 point that the end next the circuit-terminals 145 will over-balance the other end, the latter of 150 which is adapted to be held by the magnets 155 in contact therewith, the heavier end of said 160 lever being provided with a contact-point 165 adapted to contact with the circuit-terminals 170 by the breaking of the normally closed cir- 175 cuit, substantially as set forth.

3. An electric signaling apparatus, com- 180 prising a normally closed circuit and magnets 185 in said circuit, a normally open circuit hav- 190 ing the metallic separated circuit-terminals, 195 a signal in said circuit, a source of electric 200 energy common to both circuits, a lever be- 205 tween the magnets and circuit-terminals, said 210 lever being fulcrumed between its two ends 215 at such a point that the end next the circuit- 220 terminals will over-balance the other end, the 225 latter of which is adapted to be held by the 230 magnets in contact therewith, the heavier end 235 of said lever being provided with a contact- 240 point adapted to contact with the circuit-termi- 245 nals by the breaking of the normally closed 250 circuit, and a spring attached to the over-bal- 255 ancing end of said lever in a manner that its 260 disconnection from said circuit-terminals will 265 be against a spring resistance, substantially 270 as set forth.

In testimony of the foregoing I have here- 275 unto subscribed my name in the presence of 280 two witnesses.

MYRON W. PARRISH.
